kin, Bryn Mawr, Pa., assignors to Houdry Proc-
ess Corporation, Wilmington, Del., a corpora-
tion of Delaware

Application February 16, 1939, Serial No. 256,710

5 Claims. (Cl. 196—50)

This invention has to do with the conversion of very heavy and often almost worthless residual materials into more readily saleable or useful forms.

Among the materials to be treated are the great quantities of tarry or heavy bottoms in crude oils as well as the residues from refinery operations on petroleum, from the destructive distillation of carbonaceous deposits, etc. Such materials have only a limited sale for such uses as roofing compounds, road oils, and the like. Coking operations are utilized to consume much of the tarry material but the yields of gasoline are low and difficulties and delays are involved due to the frequent shut-downs which are necessary for the removal of the large deposits of coke. If the residues are to be disposed of directly as low grade fuel oil, they must be blended with very considerable quantities of light fuel oils or gas oils (which command a good price) in order to meet even bunker C specifications. Another expedient is to subject residual material to a thermal viscosity breaking operation which is considerably milder in character than the previously mentioned coking operations, the purpose being to convert the heavy charge so far as possible into gas oil for subsequent cracking and coking operations, but such viscosity breaking produces about 10% of gasoline of very low grade and octane rating as well as a corresponding or equivalent quantity of gas. Still another expedient is to prepare a vapor phase cracking charge from such residual material by a contact vaporizing operation which consists in spraying the tar in heated condition and mixed with steam or other suitable gases or vapors upon hot highly porous inert contact material and letting the hydrocarbons gradually distill off, but this operation calls for large quantities of steam or the like which must subsequently be removed and in addition lays down coky and resinous deposits in an uneven manner on and within the contact mass, thereby complicating the problem of regenerating the latter.

One object of the invention is to improve known methods of disposing of very heavy hydrocarbon residues including those which are solid at room temperature. Another object is to devise a simple and economical way of converting heavy residues so as to meet fuel oil specifications. Another object is to provide suitable apparatus for effecting the above objects. Still further objects will be apparent from the detailed description which follows.

The invention involves subjecting the heavy

hydrocarbons in liquid condition and under pressure to the action of highly porous contact material which is substantially inert or has a low or greatly reduced catalytic activity. In general, 5 the operating temperatures are at the low or lower end of the practical range for effecting catalytic cracking to produce gasoline, but the feed rates are normally higher, due consideration being given and adjustments made at times for 10 the character and/or gravity of the charge. The useful temperature range is from about 775° to 875° F. with the preferential range from 810° to 850° F. Feed rates may vary anywhere from 1½:1 (one and one-half volumes of liquid charge per hour per volume of contact mass) to 10:1. 15 Sufficient pressure is utilized to keep all of the charge and most of the products of the reaction in liquid phase, as up to 750 lbs. per sq. in. Usually, the pressure need not exceed 500 lbs. 20 per sq. in., and, in many instances, 100 lbs. per sq. in. is sufficient. The operating conditions for each type of charge are adjusted so as to produce as little naphtha and gas as possible. The 25 quantity of naphtha recovered in flashing the product to flash specifications is normally not over 5% by volume of the charge, and, in most instances, it can be held to 2% or even less. Residues from asphaltic base crudes usually require somewhat higher temperature and/or 30 lower feed rates than the residues from paraffinic or mixed base crudes.

The contact material will require regeneration from time to time to remove the coky, resinous and other solid or semi-solid deposits which 35 accumulate in the pores during the operation, hence for continuous operation two or more containers or converters are utilized, so that at least one converter may be on stream while the other or others are in regeneration. Any suitable 40 form of regeneration may be utilized, burning being the most effective, with purging operations before and after by a vaporous medium or by vacuum and with occasional flushing with a solvent after the burning operation, if desired. As 45 a preliminary step to regeneration, it is usually advantageous to send through the converter a quantity of lighter hydrocarbon material, such as a gas oil, for example, in an amount substantially equal to the volume of the contact mass, 50 to wash out of the converter the heavier charge. Such washing material is preferably sent through the converter under the pressure of the operation, the pressure then being released to permit the gas oil or other lighter hydrocarbon material to vaporize and leave the converter. This

step is not only important in preventing loss of charging material, but the wash oils may be incorporated directly with the products of the operation to make such adjustment as may be necessary to meet the desired fuel oil specifications. The quantity of lighter material needed for this purpose is readily determined during the usual laboratory tests which precede plant operations.

In order to illustrate the invention and the manner of its use, one concrete embodiment of apparatus for practising the same is indicated somewhat diagrammatically in the single figure of the accompanying drawing. The heavy residual material, heated sufficiently to be fluid, is forced by pump 1, which imposes enough pressure on the charge to retain it and subsequent products in liquid phase condition, as from 100 to 300 pounds per square inch, through a heater coil 2, where its temperature is raised to within the reaction range of approximately 775° to 875° F. The rate of feed through coil 2, however, is made sufficiently high, within the range of 1½:1 to 10:1, with due consideration to the characteristics of the charge, so that thermal cracking is substantially or practically avoided. The heated charge then passes by valved line 3 into the lower manifolding chamber 4 of converter 5, and is forced upwardly through the perforations in lower partition member 6 into and through the large central reaction chamber 7 which is completely filled with a mass M of highly porous solid contact material, in the form of bits, fragments or molded pieces, having little or no catalytic activity. The contact material may be silicious in character and may be formed after the manner disclosed in U. S. Patent No. 1,818,403, issued to Alfred Joseph on August 11, 1931. A similar material which is less inert in character may be prepared by taking about 90 parts of activated clay, such as California Superfiltrol, with about 10 parts of a plasticizing medium such as Argosite (trade name for a high swelling bentonite) to give strength, and with about 70 parts of material to product porosity, such as corn meal, these parts being thoroughly mixed and extruded into 4 mm. pellets which are then heat treated to produce the desired low degree of catalytic activity, during which treatment the corn meal is burned out to give a high degree of porosity in the pellets. The products of the reaction pass from reaction chamber 7 through perforations in upper partition member 8 into upper manifolding chamber 9, whence they pass by valved branch 10 into products line 11 leading through cooler 11a to a flashing zone provided with flashing equipment of any known or suitable type, such as tower 12. Stripping steam may be sent into the lower part of tower 12 by line 13, this steam escaping with the released naphtha and gas through overhead line 14, while the fuel oil, preferably adjusted to flash specifications, issues from tower 12 by bottom outlet line 15.

To insure accurate temperature control of contact mass M in converter 5, a heat exchange system is provided, consisting of nested heat exchange units 16 embedded in the contact mass M in symmetrical arrangement throughout the entire reaction zone, each unit consisting of an inner conduit 16a and an outer conduit 16b which may be provided with fins (not shown). The conduits connect with manifold units 17 in upper manifolding chamber 9, which manifold units comprise an inner manifolding member 17a, supplying inner conduits 16a of nested units 16, 75

and an outer manifold member 17b with which the outer conduits 16b connect. The heat exchange circuit further consists of a heat exchanger 18 and a pump 19 for circulating the heat exchange medium, which may be a fluid of any suitable or desired type, either gaseous or liquid. With the temperatures for the present operation, liquids such as water, fused salts, mercury, diphenyl, or metals or metallic alloys having low melting points, are most suitable. The heat exchange medium supplies heat to contact mass M, during the on-stream or viscosity breaking operation, to maintain the entire mass at suitable temperature, and extracts heat from the mass during the alternating regenerating period, when the deposit on the mass is burned away to prepare for another on-stream operation.

After a suitable period of operation, the charging of heavy bottoms is interrupted in order to regenerate contact mass M. As a preliminary step to the regeneration, the mass is purged of the charge. This may be effected by sending steam into the case, as through upper valved branch line 20, the dislodged fluid being vented through a lower valved line 21 serving as a drain. However, if the charge to be converted is very heavy, or if the viscosity breaking has not been sufficient to meet fuel oil specifications, it is advantageous to adjust the products by washing out the converter with a lighter hydrocarbon material, such as a gas oil, which may be charged to the converter under the same or similar pressure and temperature conditions. In many instances, only a limited amount of such wash oil is needed, as, for example, an amount approximating the volume of contact mass. While such gas oil used for the washing medium can be sent through the pump and heating equipment for the normal charge, it is preferable to utilize a separate pump 22 and coil 23, which coil may be in the same heater or still as coil 2, as indicated in the drawing, or in a separate heater. The pressure and temperature conditions are preferably identical or at least similar to the operation with the heavier charge. The heated wash oil then passes by valved branch 24 into and through converter 5, and thence to flash tower 12 in the same manner as the normal charge. The wash oil may be mingled with the charge during the period in which the latter is being shut off from the converter. Alternatively the gas oil may be introduced at the top of the converter, as by line 20, to displace the contents of the converter through line 21 to pass into products line 11 before cooler 11a, by suitable cross-over connections (not shown). After this limited washing operation, the pressure in converter 5 is released and the converter is permitted to drain by gravity into a suitable tank or container (not shown) to recover all hydrocarbons which will leave as vapor or as liquid. The converter is then steamed or subjected to vacuum purging, as through line 20, and thereafter a regenerating medium, such as air or other oxygen containing gas, is sent by line 25, preferably in heated condition and under pressure, to effect controlled burning of the deposit on the contact mass M, the fumes escaping through valved branch line 26 from the upper end of the converter. After the burning operation is completed, the converter is again purged by steam or by vacuum, and is ready to be put back on stream for another viscosity breaking operation. From time to time, it may be necessary, as a final stage in the regenerating operation, to uti-

lize inlet line 20 and drain 21 to effect solvent washing of the mass M by water, dilute acids, or other media, to extract from the mass salts or other contaminants which cannot be removed by the burning operation, as disclosed, for example, in Patent No. 1,957,649, issued May 8, 1934, to Eugene Houdry.

While it is possible to operate the process with a single converter, such as 5, there are obvious advantages in conducting the viscosity breaking operation as a continuous process. To effect a continuous operation, two or more converters 5 will be necessary, so that one or more may be utilized for the viscosity breaking operation while the other or others are in regeneration. To indicate continuous operation, two converters 5 are shown in the drawing, but the second requires no detailed description, since it is a mere duplication of the other. The converters 5 and the various lines will be lagged or jacketed to prevent heat losses, but such obvious expedients are not indicated, since they form no part of the present invention.

The use of the invention in handling very heavy residual charging material is illustrated by the following examples:

Example 1

An 8.1% tar bottoms from a mixture of Mid-Continent and East Texas crudes had the following characteristics:

Flash P. M. C. C.	F.	225
Say. U. Vis. at 210° F.		734
Pour point, ° F.		+110
Gravity, A. P. I.		12.6

To bring the above material to bunker C specifications, it was found necessary to add 54 parts of gas oil to 100 parts of the tar.

The tar, without added steam or any other vaporizing medium, was subjected to the herein described viscosity breaking operation conducted at 820° F. under 100 lbs. per square inch gauge pressure and at a feed rate of 4:1. The on-stream period was 4½ hours through a single converter. At the end of the run, gas oil in the ratio of 5 parts to 100 parts of tar was charged to the converter under the same operating conditions to wash out the converter; the products of the gas oil washing were added to the products of the viscosity breaking operation to give 102 parts of fuel oil of the following characteristics:

Flash, P. M. C. C.		154
Furol visc. at 122° F.		159
Pour point, ° F.		+25
Gravity, A. P. I.		14.5

There was also produced:

2.1% by volume of naphtha (recovered by flashing to flash specifications)
1.5% by weight of gas of 1.12 sp. gr.
0.4% by weight of coky deposit which was burned off in the subsequent regenerating operation.

Hence by employing the viscosity breaking operation, there was effected a net saving of 49 parts of gas oil (54 parts without viscosity breaking as compared with 5 parts after viscosity breaking) per 100 parts of tar.

The gas oil used for blending purposes was recycle stock from a cracking operation on a blend of East Texas crudes.

Example 2

A 32% tar bottoms from Venezuelan (Lagunillas) crude had the following characteristics:

5 Flash, P. M. C. C. 380° F.
Say. U. Vis./210° F. Too heavy.
Pour point Over (+120).
Gravity 3.4.

10 To bring this material to bunker C specifications, 122 parts of gas oil per 100 parts of tar were needed.

The tar without steam or other added material was subjected to the catalytic viscosity breaking operation at 840° F. temperature and under a pressure of 300 lbs. per sq. in., at a feed rate of 2:1 for a two hour period.

15 Only 31 parts of gas oil were then needed per 100 parts of tar to make 125 parts of bunker C fuel oil, a part of this gas oil equivalent to the catalyst volume of the converter being charged through the latter under the specified operating conditions to free the contact mass of the heavy charge. The blended fuel oil product had the following characteristics:

25 Flash, P. M. C. C. ° F. 156
Furol visc./122° F. 147
Pour point, ° F. +20
Gravity, ° A. P. I. 9.8

30 There was also produced:

1.6% by volume of 62.0° A. P. I. naphtha (recovered by flashing to flash specifications)

4.6% by weight of gas (1.15 sp. gr.)

35 2.4% by weight of coky deposit to be burned off in the subsequent regeneration of the contact mass.

By using viscosity breaking, a saving of 91 parts of gas oil (122 parts without viscosity breaking as compared with 31 parts after viscosity breaking) was effected.

From the above, it will be apparent that the present invention provides a simple and economical method of converting substantially worthless heavy residual material into salable fuel oils, without the problem of disposing of large quantities of petroleum coke. By utilizing two or more converters, a continuous operation is effected without any necessity of frequent dismantling to clean out the reaction chambers, as is required in conventional thermal coking plants. The process operates with a high charging rate, and produces only a relatively small amount of coke which is immediately burned during the alternate regenerating operations, the energy thus liberated not being wasted, but being directly recoverable in the forms of power, heat and steam. The contact mass filters out sediment, and is highly efficient as a selective viscosity breaking agent, since so little naphtha, namely, of the order of 2% by volume, is recovered. The contact mass also localizes the deposition of coke on the contact mass whence it is periodically removed by burning, prevents its deposition and accumulation in pipes, valves and other parts of the equipment, and so enables continuous uninterrupted operation under wide variation of operating conditions. Definite and practical advantages reside in the use of gas oil both as a washing medium and as a medium for effecting final adjustment of the products to fuel oil specifications; its use, however, may be minimized or even entirely avoided by recirculating or recycling a part of the products, or by making a less deep cut when the original charge is prepared.

60 The contact mass filters out sediment, and is highly efficient as a selective viscosity breaking agent, since so little naphtha, namely, of the order of 2% by volume, is recovered. The contact mass also localizes the deposition of coke on the contact mass whence it is periodically removed by burning, prevents its deposition and accumulation in pipes, valves and other parts of the equipment, and so enables continuous uninterrupted operation under wide variation of operating conditions. Definite and practical advantages reside in the use of gas oil both as a washing medium and as a medium for effecting final adjustment of the products to fuel oil specifications; its use, however, may be minimized or even entirely avoided by recirculating or recycling a part of the products, or by making a less deep cut when the original charge is prepared.

65 The contact mass filters out sediment, and is highly efficient as a selective viscosity breaking agent, since so little naphtha, namely, of the order of 2% by volume, is recovered. The contact mass also localizes the deposition of coke on the contact mass whence it is periodically removed by burning, prevents its deposition and accumulation in pipes, valves and other parts of the equipment, and so enables continuous uninterrupted operation under wide variation of operating conditions. Definite and practical advantages reside in the use of gas oil both as a washing medium and as a medium for effecting final adjustment of the products to fuel oil specifications; its use, however, may be minimized or even entirely avoided by recirculating or recycling a part of the products, or by making a less deep cut when the original charge is prepared.

70 The contact mass filters out sediment, and is highly efficient as a selective viscosity breaking agent, since so little naphtha, namely, of the order of 2% by volume, is recovered. The contact mass also localizes the deposition of coke on the contact mass whence it is periodically removed by burning, prevents its deposition and accumulation in pipes, valves and other parts of the equipment, and so enables continuous uninterrupted operation under wide variation of operating conditions. Definite and practical advantages reside in the use of gas oil both as a washing medium and as a medium for effecting final adjustment of the products to fuel oil specifications; its use, however, may be minimized or even entirely avoided by recirculating or recycling a part of the products, or by making a less deep cut when the original charge is prepared.

75 The contact mass filters out sediment, and is highly efficient as a selective viscosity breaking agent, since so little naphtha, namely, of the order of 2% by volume, is recovered. The contact mass also localizes the deposition of coke on the contact mass whence it is periodically removed by burning, prevents its deposition and accumulation in pipes, valves and other parts of the equipment, and so enables continuous uninterrupted operation under wide variation of operating conditions. Definite and practical advantages reside in the use of gas oil both as a washing medium and as a medium for effecting final adjustment of the products to fuel oil specifications; its use, however, may be minimized or even entirely avoided by recirculating or recycling a part of the products, or by making a less deep cut when the original charge is prepared.

We claim as our invention:

1. In the conversion of tars and similar residues into commercial fuel oils, the process steps which comprise sending the charge in heated condition and in liquid phase through a reaction chamber containing highly porous silicious contact material of low catalytic activity, maintaining the chamber under sufficient pressure to insure liquid phase operation, holding the contact material at conversion temperature and adjusting the feed rate to produce only a small quantity of naphtha, after a period of operation substituting for the heavy charge a quantity of lighter hydrocarbons in the gas oil boiling range substantially equivalent to the volume of the contact mass and sending it through the reaction chamber under the same operating conditions to flush the contact mass as a preparatory step to regenerating the same, limiting the on-stream operation with heavy charge to such a period that the combining of the products of the heavy charge and of the substitute charge meets fuel oil specifications, mingling the products of both charges to form a commercial fuel oil, then freeing the contact material of coky, resinous and other deposits by a regenerating operation, and repeating the above steps.

2. In the conversion of tars and similar residues into commercial fuel oils through the action of solid porous contact material which has to be freed from time to time of coky and resinous deposits in order that the converting reaction may be continued, the process steps which comprise sending the charge in heated condition and in liquid phase through a reaction chamber containing the porous contact material, maintaining the chamber under a pressure of at least 100 lbs. per sq. in. during the on-stream operation, holding the contact material at a conversion temperature and adjusting the feed rate to produce only a small quantity of naphtha and finally adjusting the products of the reaction to meet fuel oil specifications by substituting for the charge a predetermined quantity of lower boiling oil which is sent through the reaction chamber under the same operating conditions and is added to the aforesaid products, and then regenerating the contact material in preparation for another on-stream operation.

3. In the conversion of tars and similar residues into commercial fuel oils through the action of solid porous contact material, the process which comprises sending the charge at a temperature at least as high as 775° F. in liquid phase and under pressure through a reaction zone filled with the porous contact material at such rate as to produce only a small quantity of naphtha, continuing the feeding of the charge until the reaction is impaired by the deposition of coky, resinous and other contaminants on the contact material, and then prior to regenerating the contact material by oxidation feeding to the reaction zone a limited quantity of oil in the gas oil boiling range to act as a flushing medium, and add-

ing the resulting hydrocarbons to the products of the on-stream operation to adjust the same to meet fuel oil specifications.

4. In the conversion of tars and similar residues into commercial fuel oils through the action of solid porous contact material, the process which comprises sending the charge in heated condition and under sufficient pressure to maintain it in liquid phase through a reaction zone filled with porous but substantially inert contact material and maintained within the temperature range of 810° to 850° F., adjusting the feed rate with relation to the gravity and other characteristics of the charge so that the reaction produces only a small quantity of naphtha, continuing the feeding of the charge until the reaction is impaired by the deposition of coky, resinous and other contaminants on the contact material, then changing the charge to lower gravity hydrocarbons of the gas oil type but maintaining the same operating conditions, limiting the quantity of such lower gravity hydrocarbons to an amount requisite to flush the contact mass as a preparatory step to regenerating the same and to adjust the products of the reaction to fuel oil or Bunker C specifications, and mingling the products of both changes to form a commercial fuel oil.

5. In the conversion of tars and similar residues into commercial fuel oils through the action of solid porous contact material which has to be freed from time to time of coky and resinous deposits in order that the converting reaction may be continued, the process steps which comprise sending the charge in heated condition and in liquid phase through a reaction chamber containing the porous contact material, maintaining the chamber under a pressure of at least 100 lbs. per sq. in. during the on stream operation, holding the contact material at a conversion temperature and adjusting the feed rate to produce naphtha but not in excess of a recoverable quantity of 5% by volume of the charge on flashing the products to flash specifications, diverting the feeding of the charge to another reaction chamber containing similar porous contact material, washing out the first reaction chamber by sending through the latter under the same operating conditions a limited quantity of lower boiling oil, then reducing the pressure on said first reaction chamber to flash off the lower boiling oil, regenerating the contact material in said first reaction chamber by freeing it of coky and resinous deposits, then restoring the feeding of charge to said first reaction chamber while the contact material in the other reaction chamber is regenerated, and repeating the above steps to effect a continuous operation, the wash oils being used in suitable amount and added to the products of the operation to adjust the same to meet fuel oil specifications.
